UNITED STATES PATENT OFFICE.

HERMANN ALBRECHT MÜLLER, OF SCHMIEDEFELD, GERMANY.

ETHYL-CHLORIDE TUBE.

Application filed September 16, 1927, Serial No. 219,961, and in Germany June 28, 1927.

Heretofore ethyl chloride containing tubes have had a straight capillary end so that it was only possible to squirt in a downward direction. For this reason, tubes with capillary ends molten on in inclined position have been used so that the jet can be also directed to the sides within certain limits. Neither form however will eject a jet in an upward direction.

This invention relates to an ethyl chloride tube by means of which, owing to its simple and novel construction, the jet can be directed without difficulty and without special manipulations in any desired direction.

With this object in view, the capillary tube molten on the ethyl chloride tube has two capillary outlet channels, one of which is connected to a pipe arranged in the tube, and the other one terminating freely at the junction of the neck and the body of the ethyl chloride tube.

This improved tube is efficient and desirable to dispense ethyl chloride which, when affected by the hand temperature, produces a vapor and pressure that causes the liquid to flow out of one or the other capillary outlet channel according to the position in which the tube is held.

A form of construction of an ethyl chloride bottle, according to the invention (without metal closure) is shown, by way of example, in the accompanying drawing in which:

Fig. 1 is a longitudinal section.

Fig. 2 shows the capillary tube on larger scale in cross section on line A—B of Fig. 1.

The vessel 1 has an inner rising pipe 2, the upper end of which is a capillary channel 7 of a capillary tube 3 at the outlet end of the vessel. The capillary tube 3 has a second capillary channel 8, the inner end of this capillary channel 8 communicating directly with the ethyl chloride tube or vessel 1 at the junction of the tube 3 with the body.

When the tube 1 is held in the hand so that the mouth of the capillary tube 3 is upwardly directed, the heat from the hand causes vaporization so that a jet of ethyl chloride flows out through the rising pipe 2 and the capillary channel 7. The same is the case when the upwardly directed tube 1 is inclined to the right or left up to an angle of 90°.

When the tube is turned so that the outlet end of the capillary tube 3 is downwardly directed, the jet is caused to flow out through

the capillary channel 8, the same being the case when the tube 1 is inclined downwardly to the right or left at an angle up to 90°.

With the hand gripping the tube 1, a full jet of the ethyl chloride will issue from one of the capillary channels.

It is advisable to connect the lower end of the rising pipe 2 to the bottom of the ethyl chloride tube and to provide a lateral hole 6 in the same near the lower end. By this arrangement the possibility of breakage of the rising pipe by jarring or hitting the tube 1 is considerably reduced and the whole device is made more stable.

In the position of the tube 1 shown in Fig. 1 of the drawing the tube and the contents being heated by the hand, the ethyl chloride is vaporized more rapidly than it can flow out of the capillary channel 8, and this pressure, acting upon the upper end of the column of ethyl chloride will force the liquid through the hole 6 into the rising pipe 2 and out in a jet through the capillary channel 7.

The outer end of the capillary tube 3 is either closed by melting (for small-size tubes) or by any suitable form of closure.

The tube can be used for ethyl chloride and as lance-perfume and also for mixtures of ethyl chloride and other liquids possessing a low boiling point, for instance, methyl chloride, and the tube may have either a flat or round bottom.

I claim:

1. A dispensing container for ethyl chloride, comprising a main tube, a rising pipe in said main tube, and a capillary tube integral with one end of said main tube, said capillary tube having two capillary outflow channels, one of said channels communicating with said rising pipe and the other directly with the interior of said main tube.

2. A dispensing container for ethyl chloride, comprising a main containing tube, a rising pipe in said main tube integral with the bottom of said main tube and having a lateral inlet opening for the ethyl chloride adjacent the bottom of the main tube, and a capillary tube at one end of said main tube, said capillary tube having two capillary outflow channels, one of said channels communicating with said rising pipe and the other directly with the interior of said main tube.

In testimony whereof I have hereunto set my hand.

HERMANN ALBRECHT MÜLLER.
